STEAM ELECTRIC FLAT IRON

Filed Nov. 28, 1939

FIG. 1.

UNITED STATES PATENT OFFICE

2,285,757

STEAM ELECTRIC FLATIRON

Norman Smith, Syracuse, N. Y.

Application November 28, 1939, Serial No. 306,528

1 Claim. (Cl. 38—77)

My invention relates to improvements in steam electric flat irons.

In ironing cloth such as linen, cotton and the like, it is first necessary to dampen the cloth in order properly to iron out the wrinkles. In pressing cloth such as is used in men's suits and ladies' dresses, for example, woolens, serge, velvet and so on, the dampening is ordinarily accomplished by laying a damp cloth over the material to be pressed. The heat of the iron and the steam generated from the damp cloth cooperate to press the material properly. Commercial pressing machines have been constructed to expel live steam through a cloth covered pressing member to accomplish a similar result. For use on smaller articles and for use in the home, a number of flat irons have been developed which are provided with means for generating steam which is expelled through the sole of the iron to steam and dampen the material. Another type of steaming iron utilizes steam from an independent steam generator. In this latter type of flat iron, steam is conducted through the body of the iron usually from a point adjacent the heel of the iron to apertures located in the sole thereof. The flat irons of this type that are available today, usually employ electric resistance means for heating the iron itself.

The steam discharged from the iron should be substantially dry, for if the steam is so wet that the iron spits drops of water, the work may be spotted. On the other hand, the discharged steam should not be too greatly superheated, or it will not properly perform its function of moistening the clothes.

Various devices have been evolved for drying the steam within the iron. One scheme now in use employs a relatively large expansion chamber within the body of the iron at the steam inlet. This chamber is substantially filled with an absorbent heat-resisting material such as asbestos to trap out any moisture in the steam as it enters the iron. Passages lead from the expansion chamber toward the toe of the iron. Small apertures connect these steam passages with the outside surface of the sole of the iron to permit the discharge of the steam to the work. Another scheme utilizes separate baffles within the expansion chamber or steam passages to retard the flow of the steam through the iron in order that any entrained moisture carried by the steam may be vaporized by means of the heat generated by the electric resistance heating unit contained within the iron.

One of the difficulties of the schemes described

is that they require a means of access from the outside to the interior of the expansion chamber to insert the absorbent material or baffles and to replace the same as may be needed during the life of the iron. Another objection to the use of absorbent material or baffles is that the steam drying efficiency of the iron decreases with use. Another objection is the difficulty of maintaining a steam-tight cover for the opening to the expansion chamber.

An object of my invention is to provide a series of relatively small expansion chambers arranged in such fashion as to cause the steam to flow through a relatively long and tortuous passage through the body of the iron from the inlet point to the discharge point of the dried steam.

Another object of my invention is to form the expansion chambers integrally with the base portion of the iron so as to provide a steam-tight passage from the entrance point to the exit point of the steam.

A further object of my invention is to supply dry saturated steam at the exit point by keeping the steam within the body of the iron for a relatively long period of time.

Still another object of my invention is to provide a steam passage comprising a large number of small expansion chambers presenting a large surface area to the steam in order to obtain a large total amount of heat transfer from the electric heating source to assist in converting entrained moisture in the vapor into steam during its passage through the iron.

Other objects and advantages will appear from the following description and accompanying drawing, in which:

Figure 1 is a side elevation, parts being broken away and parts being shown in section, of a completely assembled flat iron made in accordance with my invention.

Figure 2 is a horizontal sectional view showing a series of expansion chambers taken on the line 2—2 of Figure 1.

Figure 3 is a vertical section, parts being broken away, taken on the line 3—3 of Figure 2.

Figure 4 is a partial horizontal section of an unfinished iron, corresponding to Figure 2 but showing the core cleaning apertures.

Figure 5 is a partial vertical section of an unfinished iron, corresponding to Figure 3 but showing the core cleaning apertures.

Referring to the drawing, 10 is a steam electric flat iron comprising a base portion or shoe 11, a cover or hood 12 and a handle 13. The handle 13 is supported above the hood 12 by

means of suitable supports 14 and 15. An electrical connection 20 is provided to connect the flat iron to a suitable source of power (not shown). A steam connection 17 has one end threaded in a suitable aperture 18 provided in the rear wall of the shoe 11 adjacent one side thereof. The other end of the steam connection 17 is connected to an independent steam generator (not shown) by means of the union 19, tube 20 and a suitable flexible conduit (not shown), which may be slipped over the end portion 21' of the tube 20.

Referring now more particularly to Figures 2 and 3, the aperture 18 enters the first of a series of expansion chambers 20, which expansion chambers are connected to each other through the relatively small passages 21. The expansion chambers 20 and connecting passages 21 are arranged to form a continuous tortuous passage for the heel of the iron to the toe chamber 22. A plurality of relatively small apertures 23 is provided in the bottom of the toe chamber 22 connecting with the outside of the sole of the iron to permit the exit of steam. Figure 2 shows clearly the steam flow path which begins where the connection 17 enters the first expansion chamber 20. From thence the steam flows laterally through the succeeding expansion chambers across the heel of the iron. It then flows longitudinally to the next series of expansion chambers through which it flows laterally. The steam progresses in like manner through each succeeding series of expansion chambers until it reaches the toe chamber 22, from whence it exits through the apertures 23. It can readily be seen that the series of small expansion chambers 20 and connecting passages 21 offer a large area of heat transfer surface to the steam as it passes through the iron. Likewise, the series of pressure drops from one expansion chamber to the next without a corresponding temperature drop in itself will vaporize entrained moisture and dry the steam.

A suitable electric resistance heating unit 25 is tightly embedded in a slot 26 which is formed by the upstanding projections 27 and 28 of the shoe 11. The width of the slot 26 in relation with the heating unit 25 is such that the unit 25 is forcibly fitted within the slot 26 to provide a heat conduction path of high thermal efficiency between the heating unit 25 and the shoe 11. The operating temperature of the iron is considerably higher than the temperature of the steam at the entrance point 17. The steam, in its long, tortuous passage through the series of expansion chambers 20 and connecting passages 21, picks up heat from the walls of the expansion chambers, thus evaporating any entrained moisture in the steam before it reaches the toe chamber 22.

The shoe 11, including the projections 27 and 28, expansion chambers 20, connecting passages 21 and chamber 22, comprises a unitary casting.

The external shape of the shoe is obtained by the method of molding well known in the casting art. The expansion chambers 20, passages 21 and toe chamber 22 are formed by supporting sand cores of suitable shape on iron or steel wires embedded in the sides of the mold. The shoe 11 is cast of aluminum, aluminum alloy or bronze which has a melting point considerably lower than the melting point of the steel wires supporting the cores, with the result that in casting the shoe 11, the supporting wires are unaffected.

After the casting is removed from the mold, the supporting wires project beyond the sides of the casting. The cast metal does not adhere to the supporting wires which are then pulled out of the casting, leaving the apertures 30 in the sides of the shoe. Through these apertures 30 the sand cores may then be removed, leaving the expansion chambers 20, passages 21 and toe chamber 22 clear. The apertures 23 are then drilled through the sole to connect the toe chamber 22 with the exterior of the iron. The apertures 30 are filled subsequently with aluminum by means of a welding operation where the shoe 11 is cast of that metal, or are drilled, tapped and plugged where the shoe 11 is of cast bronze. The exterior of the casting then is finished and a high polish given to its sole, no plating being necessary. The resulting shoe has contained within it a steam-tight, tortuous passage extending from heel to toe. The heating unit 25 is fitted into the slot 26 and suitable connections made to the exterior of the iron. The handle 13 is assembled to the hood 12 which, in turn, is removably fastened to the shoe 11 by a suitable means, such as a bolt (not shown). A heat control switch 35 of a suitable type may be provided for controlling the heat of the iron.

Although I have described a specific embodiment of my invention, I wish to be limited only by the scope of the appended claim.

I claim:

A base portion for a steam electric flat iron provided with an electric heating means, comprising a single casting including a plurality of steam chambers disposed in substantially parallel rows having small connecting passages between the upper ends of adjacent chambers in a row, and adjacent rows being similarly connected at alternate ends to form an S like series of expansion chambers progressing through said base portion to retard the flow of steam therethrough, an aperture for introducing steam into one of said chambers adjacent the heel of said base portion, a chamber located within the toe of said base portion extending a substantial distance toward the heel thereof and communicating with the last of said series of chambers, and a plurality of apertures arranged in said toe chamber and piercing the sole of said base portion to permit steam to pass therethrough.

NORMAN SMITH.
